Patented Mar. 2, 1971

220,061

COMBINED PROTRACTOR AND STRAIGHT RULE
Herb Kerns, P.O. Box 715, Florence, Oreg. 97439

Filed Feb. 2, 1970, Ser. No. 21,208

Term of patent 14 years

Int. Cl. D10—08

U.S. Cl. D52—6

FIG. 1

FIG. 2

FIG. 3

FIG. 1 is a left side elevational view of a combined protractor and straight rule embodying my new design;

FIG. 2 is a right side elevational view thereof, the arm being pivoted at an angle greater than that of FIG. 1; and

FIG. 3 is a left front perspective view.

I claim:

The ornamental design for a combined protractor and straight rule, substantially as shown and described.
